UNITED STATES PATENT OFFICE.

JOHN P. THURELL, OF NORTH ADAMS, MASSACHUSETTS.

AIRSHIP.

Application filed October 1, 1921. Serial No. 504,656.

To all whom it may concern:

Be it known that I, JOHN P. THURELL, a citizen of the United States, residing at North Adams, in the county of Berkshire and State of Massachusetts, have invented new and useful Improvements in Airships, of which the following is a specification.

This invention relates to airships and particularly to that type known as lighter-than-air machines, and has for one of its objects the provision of an aeronautical vessel of this class in which the gas bag or container is of rigid construction and so shaped externally as to function as an aeroplane.

Another object of the invention is the construction of an inherently buoyant airship provided with an upper hollow aeroplane filled with lighter-than-air gas and a lower aeroplane underlying the upper plane and 20 tiltable fore and aft along a horizontal axis.

Another object of the invention is to provide propellers arranged symmetrically on each side of the body of the airship beneath the upper aeroplane and forwardly of the lower tiltable aeroplane so that the exhaust draft from said propellers will create a pressure against the overlying portions of the upper aeroplane and against the forwardly inclined surface of the lower aeroplane, thus assisting in the support and directing of the airship.

Another object of the invention is the provision of independently operated vertically and horizontally tiltable rudders of the balanced type one of which acts also as an aeroplane and is in the path of the exhaust draft from the propellers.

Another object of the invention is to provide an inherently buoyant airship of all metal construction having a manhole in the upper surface of the gas container, substantially above the center of mass of said airship, closed by an inwardly opening cover plate of larger dimensions than said opening and provided with means for suspending said airship in a hangar.

With the above and other objects in view, my invention consists in the improved airship illustrated in the accompanying drawings, described in the following specification, and particularly claimed, and in such variations and modifications thereof as will be obvious to those skilled in the art to which my invention relates.

In the drawings accompanying and forming a part of this specification, and wherein

the preferred embodiment of my invention is illustrated:—

Figure 1 is a side elevation of the airship embodying my invention. 60

Figure 2 is a plan view of the airship with the gas retainer removed.

Figure 3 is an elevation of the front end of the airship.

Figure 4 is a plan view of the manhole 65 with the cover attached.

Figure 5 is a cross section taken along the line 5—5 of Figure 4.

In the drawings, the numeral 1 represents the body of the airship which is preferably 70 made from a light metal such as aluminum or one of its alloys and is supported on the ground wheels 2. Within, the body, is equipped with seats and forms the living quarters for the crew of the airship. 75

Carried transversely toward the forward end of the body 1 is a horizontal platform 3 which extends outwardly from opposite sides of the body and is substantially braced to the sides thereof by the inclined members 4 which are best shown in Figure 3. Said platform and bracing members are arranged to present an edge thereof longitudinally of direction of movement of the airship in order to minimize the head resistance of 85 the airship when the latter is in motion. Supported on the outer ends of the platform 3 are the engine blocks 5 each of which carries a forwardly directed propeller 7. The engine may be driven together or separately as may be desired and neither the 90 structure of the engines nor the mode of operating them is to be construed as a part of this invention.

Supported by the body is a light metallic 95 super-structure comprising a pair of upper tension members 8 outwardly flanged as at 16 and a pair of lower tension members 9 the members of each pair being supported a fixed distance apart by horizontal spacing bars 10 and the pairs being separated by vertical struts 11 secured therebetween at regular intervals. The tension members of each pair come together at the front giving a prow shape to the forward end of the 100 super-structure.

This super-structure extends to the rearward of the body a substantial distance and the forward portion thereof carries on its upper side the gas container 12 which is 110 made of aluminum or some light alloy which is characterized by tensile strength. The top

of the gas container consists of a flat sheet 13 to the under part of which is secured the elongated convex envelope 14. The surface of the latter is designed with stream-line 5 contour as is also the front of the body 15 in order to present as little head resistance as possible to the air when the airship is in motion. The top 13 extends beyond the envelope 14 on all sides and cooperates therewith to function as an aeroplane in assisting in the support of the airship. The aeroplane 12 is securely anchored to the flanges 16 of the tension members 8 by means of stay bolts 17 which extend through the gas container 10 and are secured by nuts to said flanges 16 and to the top 13 of the gas container. The rear end of the top 13 and the super-structure are mutually braced by the inclined members 18. The gas container 12 is preferably lined with gas proof fabric to ensure against leakage through the metallic joints between the top and the envelop 14.

That portion of the super-structure which overhangs the body to the rear carries the 25 rudder controls comprising the horizontal rudder 19 and the vertical rudder 20. These 30 rudders are of the balanced type, that is they are symmetrical on both sides of their axes of rotation. By this construction it is provided that the air pressure on one-half of the rudder is exactly balanced by the pressure on the other half so that there is no tendency of said rudders to tilt from any extraneous cause but only in obedience to the 35 positive control means by which their movements are directed. In the embodiment of my invention shown the vertical rudder 20 swings about an axis which is supported by the rearmost pair of horizontal spacing 40 members 10 and the horizontal rudder swings about an axis of support which is journaled in an intermediate pair of the vertical struts 11.

The rudders are controlled by flexible cables 21 and 22 each of which is suitably attached at both ends to its respective rudder and wound several times around an independent drum or windlass 23 or 24 which is controlled by the handle 25. By winding 50 the cables around the windlasses 23 and 24 slippage is prevented and the rudders are positively controlled in both directions.

The horizontal rudder extends transversely on either side of the super-structure 55 and into the path of the exhaust from the propellers 7. It also lies in a position superposed by the upper aeroplane 12. In this position the rudder is enabled to take advantage of the powerful draft of exhaust air which passes rearwardly from the propellers and which materially assists the rudder in elevating or depressing the airship.

In order to prevent rolling or pitching of the airship the body 1 is provided with longitudinal rigid wings 26 extending out-

wardly and acting by their resistance against the air as stabilizers for the machine.

Gas is admitted to the container 12 by the gas cock 27 connected to the under surface of the envelope 14, and a manhole 28 is provided in the top 13 of the gas container at a point substantially above the center of mass of the airship. Said manhole is large enough to permit the entrance of a man into the gas container for the purpose of making repairs, and is covered by an inwardly opening cover plate 29 which is made larger than said manhole and abuts against the inner surface of the top 13. The edge of the manhole is strengthened by the substantial reinforcing plate 31 against which the bars 32 are clamped by bolts secured to the cover plate in order to fasten the latter in gas tight relation to the manhole. The cover plate is made of strong material and carries the hook 30 by which the airship may be suspended when in the hangar.

Having described my invention what I claim as new and desire to secure by Letters Patent, is:—

1. An airship comprising a body, an aeroplane secured to said body, said aeroplane having a flat upper wall, a concave lower wall cooperating with said upper wall to form a gas-tight chamber having a convex lower surface including a sloping rear portion, an engine driven propeller carried by the forward part of said body beneath said aeroplane and a horizontal tilting rudder carried beneath said aeroplane and rearwardly of said sloping portion and in the path of the exhaust draft from said propeller.

2. An airship comprising a body, a hollow aeroplane having a flat upper surface and convex lower surface formed by attached walls, enclosing a gas-tight chamber, said aeroplane being secured to said body by stay bolts passing through an element of said body and through said gas-tight chamber to the upper wall thereof.

3. An airship comprising a body, a hollow aeroplane having a flat upper surface and convex lower surface formed by attached walls, enclosing a gas-tight chamber, an engine driven propeller carried by the forward part of said body beneath said aeroplane, horizontal and vertical rudders supported by said framework to the rearward of the body, said horizontal rudder lying beneath said aeroplane and rearwardly of said convex surface in the path of the exhaust draft from said propeller.

4. An airship comprising a body, a hollow aeroplane having a flat upper surface and convex lower surface formed by attached walls, enclosing a gas-tight chamber, engine driven propellers carried by the forward part of said body on opposite sides thereof beneath said aeroplane and a hori-

zontal tilting rudder having the surface thereof equally distributed on each side of its axis of rotation, said rudder being carried beneath said aeroplane to the rear of 5 said convex surface and in the path of the exhaust draft from said propeller.

5. An airship comprising a body, a hollow aeroplane having a flat upper surface and convex lower surface formed by attached walls, enclosing a gas-tight chamber, 10 means for securing said aeroplane to an element of said body, comprising stay bolts secured to said element at one end and passing through said gas-tight chamber to the 15 upper wall thereof, said aeroplane and body being constructed of a light metal.

6. An airship comprising a body, a hollow aeroplane having a flat upper surface and convex lower surface formed by attached walls, enclosing a gas-tight chamber, 20 means for securing said aeroplane to said body comprising stay bolts anchored at their opposite ends to the flat upper wall and said body respectively, said flat upper wall 25 being provided with a man hole, an inwardly opening cover for said manhole, said cover being of larger dimensions than said man-

hole and abutting the inner side of the peripheral edge of said manhole when closed.

7. An airship comprising a body, a hollow aeroplane having a flat upper surface and convex lower surface formed by attached walls, enclosing a gas-tight chamber, 30 said aeroplane being secured to said body by stay bolts anchored at their opposite ends to the upper wall of said aeroplane and to said body, said upper wall being provided with a manhole located substantially above the center of mass of said airship, a reinforcing plate surrounding said manhole, an 35 inwardly opening cover for said manhole, said cover being larger in dimensions than said manhole so as to abut the inner surface of the peripheral edge of said manhole when in closed position and a hook secured to said 40 manhole cover for suspending said airship in a hangar.

In testimony whereof I have hereunto set my hand in presence of two subscribing witnesses.

JOHN P. THURELL.
